UNITED STATES PATENT OFFICE

2,617,005

WARMING DEVICE

Herman Ray Jorgensen, Pasadena, Calif.

Application March 15, 1950, Serial No. 149,755

2 Claims. (Cl. 219—19)

1

This invention relates to a warming device and it is primarily an object of the invention to provide an article of this kind especially designed and adapted for use by animals.

It is also an object of the invention to provide an article of this kind in the nature of a bed including electrical heating means having a normally open operating circuit together with means whereby the weight of the animal occupying the device effects the closing of the circuit.

Furthermore it is an object of the invention to provide a device of this kind embodying the use of a plurality of heating media which automatically become inoperative at varying temperatures.

The invention consists in the details of construction and in the combination and arrangement of the several parts of my improved warming device whereby certain advantages are attained, as will be hereinafter more fully set forth.

In order that my invention may be better understood, I will now proceed to describe the same with reference to the accompanying drawings, wherein:

Figure 1 is a vertical sectional view taken substantially on the line 1—1 of Figure 2;

Figure 2 is a view in top plan of the device as herein comprised with a portion broken away and parts indicated by broken lines; and

Figure 3 is diagrammatic view of the heating elements as herein comprised.

In the embodiment of the invention as illustrated in the accompanying drawings, T denotes a tray-like base member of preferred dimensions and depth and preferably of metal. Within the lower portion of the tray T is a bed 1 of a material that is a heat and electrical insulator and upon which rests a heating unit A which snugly fits within the tray T. At substantially the center of the body plate 2 of the heating unit A is a conventional type of single pole single throw normally open spring switch 3 including the upstanding operating lever 4 which is engaged from above by the free end portion of an elongated spring arm 5. The opposite end portion of the arm 5 is riveted, as at 6 or otherwise rigidly secured to a side wall 7 of the tray 7.

The side walls 7 of the tray T have their upper margins defined by the outwardly disposed flanges 8 to which are suitably secured, as at 9, the marginal portions of a cover 10. This cover 10 is preferably of metal and is made sufficiently over-size to allow flexing. The free end portion of the spring arm 5 contacts from below with the central portion of the cover 10 and nor-

2

mally maintains said central portion in raised position as shown in Figure 1 of the drawings.

The switch 5a is interposed in one of the conductors *a* comprised in the circuit for the primary coil 13 of a transformer 11. This transformer is of a conventional type to reduce the line voltage to twenty-four volts.

Carried by the body or plate 2 of the heating unit A are the heating elements 12 and 14. The element 12 is in electrical connection with the secondary coil 15 of the transformer 11 by the conductors *b* and *c*. Interposed in the conductor or leg *b* is a bimetal thermostat 16 set to open at 85° F. Interposed in the conductor or lead *c* is a bimetal thermostat 17 set to open at 95° F.

The heating element 14 is interposed between the thermostats 16 and 17 and is in electrical connection with the thermostat 16 through the conductor or leg *d* and with the thermostat 17 through the conductor or leg *e*.

The transformer is herein disclosed as mounted upon a corner portion of the tray T and it is to be understood that the thermostats 16 and 17 may be set to open at temperatures other than hereinbefore mentioned.

The conductors *a* extend exteriorly of the tray for connection with a desired source of electrical energy. The conductors *a* exteriorly of the tray are disposed through and around cable 18 to assure that an animal will be unable to bite into the conductors *a*.

Interposed in one of the conductors or legs *a* for the primary coil 13 of the transformer 11 is a fuse 19 of desired capacity and which is provided in the event of an electrical failure.

When the device is occupied by an animal, the weight of said animal will close the switch 3 whereupon the heating elements 12 and 14 will become effective. The element 12 may be referred to as an auxiliary heating element. When a temperature of 85° F. is reached or such other degree to which the thermostat 16 is set, the thermostat will open and the element 12 will cease to contribute heat. When the device attains a temperature of 95° F. or such or other degree to which the thermostat 17 is set, the thermostat 17 will open and the element 14 will cease to contribute heat. It is to be noted that the wiring is so arranged that if there should be a failure in thermostat 16, the opening of the thermostat 17 will deenergize both heating elements 12 and 14.

Disposed over the body plate 2 of the heating unit A is a thin sheet 20 of asbestos or the like.

From the foregoing description it is thought to be obvious that a warming device constructed in accordance with my invention is particularly well adapted for use by reason of the convenience and facility with which it may be assembled and operated.

I claim:

1. A device of the character described comprising a tray-like base member having side walls, a flexible cover overlying the top face of the member and secured to the walls thereof, a spring arm underlying the cover and having one extremity secured to one of the side walls, the opposite extremity terminating at the central portion of the cover, an electrical heating unit within the tray-like member, an operating circuit therefor, a normally open switch interposed in said circuit, and an operating lever for the switch engaging the spring arm from below whereby depression of the cover and arm will move the lever to close 15 the switch.

2. A device of the character described comprising a body member of insulation material, two electrical heating elements carried by and overlying the body member, a main circuit for 25 one of the elements, a circuit for the second element in parallel with the main circuit, a normally closed thermostatic switch interposed in

each of the circuits, the switch in the main circuit opening at a lower temperature than the switch in the parallel circuit, a current supply circuit including a primary winding of a transformer, the secondary of the transformer being in said main circuit, a control switch interposed in the current supply circuit, and a shiftable means overlying the body member and operatively coupled with the control switch for closing the same, one of said thermostatic switches being common to the circuits for the two electric heating elements.
